UNITED STATES PATENT OFFICE.

AXEL W. NILSSON, OF PORT WASHINGTON, NEW YORK.

SWIMMING DEVICE.

Application filed September 21, 1922. Serial No. 589,572.

To all whom it may concern:

Be it known that I, AXEL W. NILSSON, a citizen of the United States of America, and a resident of Port Washington, Long Island, county of Nassau, and State of New York, have invented certain new and useful Improvements in Swimming Devices, of which the following is a specification.

My invention relates to swimming devices for use by human beings, and has for its object to provide a simple and efficient device capable of being readily attached in position and whereby self-propulsion of the human body through the water in the act of swimming is greatly facilitated. The invention will be fully described hereinafter and the features of novelty will be pointed out in the appended claims.

In the accompanying drawings, which illustrate an example of the invention without defining its limits, Figure 1 is a perspective view showing the device in operative position upon a swimmer; Fig. 2 is an elevation thereof; Fig. 3 is an inverted plan view, and Fig. 4 is a view illustrating the method of attachment of the device.

As shown in the drawings, the device comprises one or more, and preferably two, rectangular frames 5 located in spaced, parallel relation and having their inner members secured to a carrying element 6 and the outer members fixed upon supporting rods 7, as shown in Fig. 1. The element 6 and rods 7, in turn, are mounted upon a foot-piece 8 which is shaped to follow the conformation of the human foot and to provide a rest therefor; the foot-piece 8 is somewhat less in length than the foot for which it is intended, so that when the device is worn, the toes and forward end of the foot will be free and unobstructed to enable the wearer to climb out of the water, for instance by way of a ladder. A plurality of blades 9 are pivotally mounted in groups in the frames 5 to rotate about axes which extend in planes parallel to the plane of operative movement of the device and transverse to the direction of such movement, and which are approximately perpendicular to the leg of the swimmer and project outwardly therefrom when the device is in place, as illustrated in Fig. 2; in the preferred construction the pivots of the blades are offset with respect to the longitudinal centre lines thereof, so that each blade will quickly assume an operative position at the proper

time, it being understood that suitable stops may be provided to arrest the swinging movements of said blades at predetermined points. In order to insure the proper operative co-operation of the blades 9, they may be connected in any suitable manner to move in unison, as by means of a rod or the like 9^b. In the illustrated example the arrangement is such that the surface area of each group of blades is in excess of the surface area of a foot of the swimmer, so that a maximum propelling force is developed with a minimum of physical energy. Any suitable attaching means may be provided for securing the device in place; for instance, as shown, the foot-piece 8 may be constructed with apertures 10 for the accommodation of straps 11 which extend about the foot above the instep and provide a seat for the heel and further encircle the carrying element 6 and the leg above the ankle, as shown in Fig. 2. Furthermore, a strap 12 may extend through an aperture 13 in the foot-piece 8 and over the foot near the base of the toes, while another strap 14 may pass through an opening 15 near the upper end of the element 6 and about the leg, as also illustrated in Fig. 2.

The rods 7 and frames 5 are preferably constructed in tubular form for strength and lightness and so that the air confined in these hollow frames provides the buoyancy which causes the device to be suspended in the water without effort; all parts of said device are, for instance, made of aluminum alloy for strength and lightness and so that the dead weight of the device, when out of the water, is relatively low, and when in the water, is easily maintained by the specific gravity of water and has no tendency to sink. The rods 7 and frames 5, by enclosing the blades 9, constitute guards which prevent said blades from inflicting injuries to others when the wearer of the device is walking about.

In practice, the device is located upon the outside of the legs and occupies the position shown in Fig. 1, in which it does not interfere with the walking or other movements of the wearer and, because of the dimensions of the foot-piece 8, permits the forward parts and toes of the feet to be freely used for climbing from the water and the like. As the swimmer draws the legs upward in the act of swimming, the blades 9 will occupy positions in which the

edges thereof are presented to the water, which accordingly is cut through by said blades and presents practically no resistance thereto, so that this movement of the legs 5 is accomplished with practically no more effort than is required without the device. As soon as the legs kick backward, the pressure of the water causes the blades 9 to be pivotally swung to positions in which the 10 surfaces thereof are presented to the water, this shifting of the blades being facilitated because of the off-set positions of the pivots. To still further insure this adjustment of said blades, a corner of each of them may 15 be bent slightly out of the plane of each blade, as indicated at 9^a, so as to present a surface, when the blades occupy their inoperative positions, upon which the water may act to swing them to their operative 20 positions as soon as the rearward kick of the legs is commenced, or said blades may be otherwise deformed to produce the same result. In any event, as the legs describe rearward movements, the blades 9 will be 25 squarely presented to the water, which accordingly acts thereon to resist this rearward movement and therefore develops a pressure which serves to propel the swimmer in a forward direction. As the legs 30 are again drawn toward the body, in a movement of recovery, the blades 9 are again pivotally shifted toward their inoperative positions, in which they cut through the water without any appreciable effort. 35 The pivotal rocking of the blades to and from their several positions is facilitated and assured because said blades may be said to be overbalanced due to the offset position of the pivots; as a result of this, the 40 major area of each blade lies to one side of its pivot and provides a surface upon which the water may act to automatically adjust the blades as described, the resistance to such adjustments which is offered 45 by the relatively lesser area of each blade which lies upon the opposite side of its pivot being readily overcome.

Because of the fact that the axes about which said blades rock or oscillate lie in 50 planes parallel to the plane of operative movement of the device and extend in directions transverse to such movement and approximately perpendicular to the legs to which the device is attached, the entire surface area of all of the blades is quickly 55 brought to an operative position and is simultaneously used throughout its entire extent to produce a pressure upon the water whereby the swimmer is propelled; at the 60 same time, with the described arrangement, the blades are brought to an inoperative position at once, at the beginning of each movement of recovery of the legs. This is in contradistinction to that class of devices 65 in which the blades swing in arcs toward

and away from the legs and in which the surface area of said blades comes progressively into use, and in the same way, presents a progressively decreasing resistance whereby the movement of recovery of the 70 legs of the swimmer is hampered and hindered.

The present device is extremely simple in construction, is comfortable to wear, and does not interfere with the walking and 75 other movements of the wearer; being of a buoyancy corresponding approximately to the specific gravity as water, it does not require any force or strength to be expended 80 in supporting it while the wearer is actually in the water, but may be said to be self-sustaining. The multiplicity of blades which it is possible to include in the device without rendering it cumbersome or complicated results in a high speed of propulsion 85 being attained with comparatively little manual effort on the part of the swimmer. The device is easily attached in position and may be removed from the wearer at will 90 without difficulty; at the same time, it is 95 capable of being easily carried about.

Various modifications may be made within the scope of the claims without departing from the nature of my invention, as set forth in the appended claims.

I claim:

1. A swimming device comprising a foot-piece of less length than the foot it is intended to accommodate and arranged to leave the toes of a swimmer free and unobstructed, a carrying element mounted on said foot-piece toward the rear thereof and adapted to extend lengthwise of a leg of the swimmer, hollow rods fixed upon said foot-piece, spaced, rectangular frames carried by said element and rods in approximately perpendicular relation to said element, blades pivotally mounted in said frames in groups and enclosed thereby, said blades being movable about axes perpendicular to said element, and straps whereby said element and foot-piece are detachably secured in place to attach the device to a swimmer.

2. A swimming device comprising a foot-piece, a carrying element mounted thereon and adapted to extend lengthwise of a leg of the swimmer at the outside thereof, a plurality of hollow-air-containing frames extending outwardly from said carrying element in spaced, superimposed relation to each other, hollow air-containing rods connected with each of said frames and with said foot-piece and a plurality of blades pivotally mounted on each frame and enclosed thereby.

3. A swimming device comprising a support, adapted to extend lengthwise of the leg of the swimmer at the outside thereof, a plurality of blades pivotally mounted on said support to swing about axes extending

- outwardly at approximately right angles to the leg of a swimmer, said blades being deformed in a predetermined manner to present a surface which is immediately responsive to the pressure of water during the swimming movements, whereby the blades are pivotally actuated in a positive manner from one position to another, and means for securing said device to the leg of a swimmer.
- 10 4. A swimming device comprising a support, a plurality of blades pivotally mounted thereon to swing about axes extending out-

wardly at approximately right angles to the leg of a swimmer, each blade having a corner bent out of the surface plane of the blade 15 to present a surface which in all positions of said blade is immediately responsive to water pressure during the swimming movements to positively swing said blades from one position to another, and means for securing said device to the leg of a swimmer. 20

In testimony whereof I have hereunto set my hand.

AXEL W. NILSSON.
